UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS, A CORPORATION OF ILLINOIS.

HOPPER-CAR.

1,257,270.

Specification of Letters Patent. Patented Feb. 19, 1918.

Application filed January 22, 1916. Serial No. 73,571.

To all whom it may concern:

Be it known that I, ARGYLE CAMPBELL, a citizen of the United States, residing at Chicago, in the county of Cook and State 5 of Illinois, have invented a certain new and useful Improvement in Hopper-Cars, of which the following is a full, clear, concise, and exact description, reference being had to the accompanying drawings, forming a 10 part of this specification.

This invention relates to improvements in hopper cars.

An object of the invention is to provide a hopper car, particularly of the so-called W 15 type having increased load carrying capacity as compared with present types now in service.

Another object of the invention is to provide a hopper car having increased capacity 20 as compared with present commercial types wherein part of the load is carried by an improved type of hopper door.

A still further object of the invention is to provide a hopper car of the W type which 25 may be made longer than those now in use to thereby increase its capacity and at the same time maintain the height and slope of the central, transverse cross ridge of the car.

The invention furthermore consists in improvements in the parts and devices and in the 30 novel combinations of the parts and devices hereinafter described and made the subject matter of claim.

In the drawing forming a part of this 35 specification, Figure 1 is a part side elevation and part longitudinal section of a hopper car showing my improvement in connection therewith. Fig. 2 is an enlarged detail, vertical sectional view near the longitudinal center of the car showing the improved arrangement, the dotted lines indicating one of the hopper doors in open position and other dotted lines being employed to more clearly illustrate the method 40 of obtaining increased capacity. Fig. 3 is an enlarged, vertical transverse sectional view taken substantially on the line 3-3 of Fig. 2. And Fig. 4 is another detail, sectional view similar to Fig. 2 illustrating 45 a different type of hopper door which may be employed in carrying out my invention.

In said drawing, 10-10 denote the side walls of a W type of car, 11-11 the downwardly and inwardly inclined hopper bottom sheets, 12-12 the inner longitudinal

hopper sheets having the outwardly offset portions 13-13 near the hopper door openings for the purpose hereinafter specified, 14-14 the outer longitudinal hopper sheets which are inclined toward the transverse 60 center of the car, and 15-15 the ridge sheets which meet at an angle at the longitudinal center of the car. As will be understood from an inspection of the drawing, there are four hoppers arranged in pairs on opposite sides of the center sill 16 of the car and the door openings for each hopper are formed between the lower edges of the bottom hopper sheets 11 and the lower edges of the inclined ridge sheets 15. 65

The improved hopper doors are designated generally by the reference A and, as shown, each hopper door A is of substantially scoop or pan shape and is provided with a vertically extending back wall 16, a 70 lower horizontal bottom wall 17 arranged substantially at right angles to the back wall 16 when the door is in closed position, and side walls 18-18. Each door A is provided on its sides with upwardly extending 75 brackets 19-19 flanged at their edges as indicated at 20 for strength, each of said brackets 19 having a hinge casting 21 at its upper end, the outer hinge casting 21 being pivotally mounted on a hinge pin 22 supported in suitable castings 23 and 24, secured 80 respectively to the inner side of the longitudinal hopper sheet 14 and lower portion of the side wall 10. Each of the inner hinge 85 castings 21 is pivotally mounted on a hinge pin 25 which extends through the center sill and the offset portion 13 of the inner longitudinal hopper sheets 12, the latter having suitable bearing brackets 26-26 fastened thereto to form a proper support for the 90 hinge pin 25. The upper transversely extending edge of each hopper door 18 is adapted to fit over an angle iron 27 secured to the under side of the lower edge of the ridge sheet 15 and at its lower transverse 95 edge, each hopper door A is offset from the main bottom portion 17 as indicated at 28, and is further provided with an edge flange 29 adapted to fit over an angle 30 secured to the under side of the lower edge of the bottom hopper sheet 11. It will also be apparent that the sides 18-18 of each hopper door A fit over the outwardly offset portions 13 of the inner longitudinal sheets 12 and the outer longitudinal sheets 14 whereby the 100 105 110

door openings are properly sealed when the hopper doors are in closed position.

As appears from an inspection of Figs. 1 and 2, the doors swing about axes located a considerable distance above the top edges of the door openings so that as the doors are swung open, they clear the rail 31. Any suitable door operating mechanism may be employed, that shown in the drawing comprising a transversely extending channel 32 connected to the undersides of a pair of doors, a bracket 33 secured to said channel between the hoppers, an eye bolt 34 mounted on said bracket and channel, an elongated hook shaped link 35 pivoted to the eye bolt 34, a short link 36 pivoted to the link 35 and another link 37, the latter in turn being pivoted to an arm 38 formed integrally with a drum fixed to a transversely extending operating shaft 39. The latter extends to the sides of the car and is provided with any suitable form of ratchet 40, pawl 41 coöperable therewith and locking cam 42. The door mechanism is of a well known type and is so arranged that when the doors are in closed position, tendency of the shaft to rotate is eliminated on account of the hook shaped link 35 engaging the drum to one side of a line drawn between the axis of the operating shaft and the pivotal connection between the eye bolt 34 and link 35. As will be understood, the doors are operated in pairs, there being two sets of door operating mechanisms.

By referring to Fig. 2, it will be seen that the slope and height of the ridge sheets 15 are maintained even though the length of the car is increased. If the arrangement which I have shown were not employed and the car were lengthened as compared with those now in service, the ridge sheets would necessarily occupy the position indicated at dotted lines 43 since the usual type of door and hinging arrangement would have necessitated hinging the doors at a point as indicated at 44, in order that the doors could swing and properly clear the rail. Hence, it will be seen that with my improved arrangement I obtain the additional capacity represented by the volume between the ridge sheets 15 and the imaginary location of the ridge sheets indicated at 43 and the additional triangular shaped volume located by the dotted line 45. Furthermore, by employing hopper doors of the character shown and described I obtain additional capacity equivalent to four times the load carrying capacity of each scoop or pan shaped door. In this connection, it will be understood, of course, that the slope of the ridge sheets is necessarily determined by the material which the car is designed to carry in order to insure a complete discharge of the load and prevent "bridging" or "arching" of the load.

In the form shown in Fig. 4, the arrangement of hopper sheets, ridge sheets, door operating mechanism, door hinging devices, and location of the door hinge points are the same as those in the car illustrated in Figs. 1, 2 and 3. The hopper door A', however, approaches more nearly the hopper doors now in use and illustrates that such a type of hopper door may be employed and still obtain increased capacity for the car by pivoting it in the manner described, as it will be obvious that with this arrangement I also obtain the increased capacity heretofore described in connection with the ridge sheets.

I have herein shown and described what I now consider the preferred means of carrying out my invention but the same is merely illustrative and I contemplate all changes and modifications that come within the scope of the claims appended hereto.

I claim:

1. A car having hoppers located on opposite sides of the center sill, each hopper having a longitudinally extending outer hopper sheet inclined with respect to the corresponding side wall of the car to thereby form a space between each of said hopper sheets and the side walls, and an inner longitudinal hopper sheet a portion of which is spaced from the center sill, said car being provided with hinged doors for each of the hoppers, each of said doors being hinged in said spaces between the hopper sheets and side walls and hopper sheets and center sill.

2. A hopper car having hoppers located on opposite sides of the center sill, each hopper being provided with a side hopper sheet inclined with respect to the side wall of the car and forming a space with the lower portion of the latter, and an inner longitudinal hopper sheet spaced from the center sill of the car, hopper doors for each of said hoppers, and means for hinging said doors in said spaces, the axes about which said doors swing being located above the upper edges of the door openings.

3. A hopper car of the W type having a transverse central ridge and pairs of hoppers on each side of the center sill, each hopper including inner and outer longitudinally extending side sheets and an inclined bottom sheet, each hopper having a door opening formed by the lower edges of the respective hopper bottom sheet, ridge and side sheets, and a door for each hopper, each door being pivoted to swing about a transverse axis located above the lower edge of the adjacent portion of the ridge sheet, said axis extending through the side sheets of the respective hopper.

4. A car having hoppers, each hopper having an inclined bottom sheet and side sheets, a door for each hopper, and means

for pivotally supporting each door, each of said means including a hinge secured to each side sheet, said hinges being located above the adjacent upper edge of the door opening of the hopper.

5. A hopper car of the character described having hoppers on each side of the center sill of the car, each of said hoppers including an inclined hopper bottom sheet and 10 inner and outer side sheets extending longitudinally of the car, said inner side sheets being spaced from the center sill, hopper doors for the hoppers, and means for pivotally mounting said doors to swing about 15 transverse axes, said means including pivotal connections located in the spaces between the center sill and said inner side hopper sheets.

6. A hopper car of the W type having 20 pairs of hoppers on each side of the center

sill of the car, each hopper including an inclined hopper bottom sheet and longitudinally extending inner and outer side hopper sheets, the inner side hopper sheets being spaced from the center sill of the car, and 25 the outer side hopper sheets, at their upper ends, being spaced from the lower edges of the sides of the car, transversely extending hopper doors for the hoppers, and means for pivotally supporting said doors to swing 30 about axes extending transversely of the car, said means including pivotal connections located in the spaces between the outer side hopper sheets and the side walls of the car and between said inner side hopper sheets 35 and the center sill.

In witness that I claim the foregoing I have hereunto subscribed my name this 20th day of January, 1916.

ARGYLE CAMPBELL.
